UNITED STATES PATENT OFFICE.

WILLIAM F. REYNOLDS AND WILLIAM A. CATHEY, OF HOUSTON, TEXAS.

DISPLAY APPARATUS.

Application filed September 4, 1923. Serial No. 660,953.

To all whom it may concern:

Be it known that we, WILLIAM F. REYNOLDS and WILLIAM A. CATHEY, citizens of the United States, residing at Houston, in the county of Harris and State of Texas, have invented certain new and useful Improvements in a Display Apparatus, of which the following is a specification.

This invention relates to new and useful improvements in a display apparatus.

One object of the invention is to provide an apparatus of the character described, specially designed for use in connection with cold drink stands, and at similar places, for the purpose of advertising and displaying the drink being sold. As illustrated in the drawings, the device has been designed for the special purpose of displaying and advertising fruit juice drinks, particularly orange juice, although the apparatus is capable of various embodiments to adapt it to the particular use for which it may be desired.

Another object of the invention is to provide an advertising and displaying device which is of novel construction and attractive in appearance.

A further feature of the invention resides in the provision of an advertising and displaying apparatus which is of very simple construction and may be cheaply constructed and easily and economically operated.

With the above and other objects in view, the invention has particular relation to certain novel features of construction, operation, and arrangement of parts, an example of which is given in specification, and illustrated in the accompanying drawings, wherein:

40 Figure 1 shows a front elevation of the device.

Figure 2 shows a vertical sectional view, and,

Figure 3 shows a rear view of the operating mechanism, partly in section.

In the drawings, the numeral 1 designates a case which is formed to represent a pot, and the numeral 2 designates the representation of a fruit tree which is anchored in said pot. As shown, an orange tree is represented. The numeral 3 designates the trunk of the artificial tree which is preferably tubular in form and composed of strong material such as sheet metal. The

case is sustained on a suitable base as 4. The 55 numeral 5 designates a vertically extending transverse partition or wall, which is located behind the artificial tree, so as to hide the operating mechanism, as well as to form a support therefor. There is a frame work 60 fastened to this wall in the rear designated as a whole by the numeral 6. Suitable pulleys as 7 and 8 are fastened to the respective shafts, 9 and 10, and these rotate in suitable bearings, in the respective bearing 65 supports 11, 11, and 12, 12, forming the upper and lower timbers of the supporting frame-work. Over these pulleys there operates an endless belt 13, and spaced apart 70 along this belt on the outside are the lugs 14, forming carriers for the individual oranges or other fruit, 15. Mounted in the frame-work 6 there is a suitable motor 16, whose shaft has a worm gear 17, which is in mesh with and drives a similar gear 18, 75 fixed on the transverse shaft 19. This shaft has a large pulley 20, fixed thereon which is aligned with a similar smaller pulley 21, which is fixed on the shaft 22 above the 80 motor. This last mentioned shaft is suitably mounted to rotate in bearings carried by the frame-work, and has a large pulley 23, fixed thereon in alignment with a similar smaller pulley 24 which is fixed on the shaft 9. The pulleys 21 and 24 are driven 85 by the respective belts 25 and 26, which are in turn driven by the corresponding pulleys 20 and 23. Through the mechanism described, the elevator apron 13 is driven.

There is a looped conduit 27, one arm of 90 which extends up through the trunk 3 of the artificial tree, and a section of this conduit, as 28, is formed of glass or other transparent material and is located in front of said trunk, so as to be visible, as shown in Figures 1 and 2. This conduit extends through the partition wall 5 and incorporated with it there is a suitable pump 29. This pump is of any well known construction, and it is not thought necessary to show the details thereof. The pump impeller shaft 30 has a pulley 31, fixed thereon, which is aligned with a pulley 32, which is fixed on the shaft 22, and a belt 33 drives the pump, the same being driven by the pulley 32. Connected 100 into the looped conduit 27, there is a stand pipe 34, and through this stand pipe the looped conduit 27 may be filled with the

drink to be displayed, and the pump will keep up a constant circulation of the fluid through the conduit 27, which will be displayed through the transparent section 28.

5. Leading from the upper end of the conveyer 13 there is a trough-like chute 35, which is spiraled around the tree and whose lower end diverges rearwardly through the partition 5, and is formed into a hopper 36. 10 The front side of this hopper is inclosed by the belt 13, and the bottom of the hopper has a cut-away portion 37, permitting the passage of the lugs, or carriers, 14. The fruit, as 15, are elevated one at a time by the carriers 14, to the top of the elevator, and they fall into the chute 35, and pass down the same by gravity, around the spiraled portion thereof, and are delivered into the hopper 36 successively, and as delivered they 20 are picked up by the elevator and again elevated, thus repeating the cycle.

All of the operative mechanism is hidden by the partition 5, and only that part of the apparatus shown in Figure 1 is visible, thus 25 presenting a unique and attractive appearance, and forming an effective display of the drink being sold, as well as being an effective advertisement thereof.

What we claim is:—

- 30 1. An apparatus of the character described, including the simulation of a fruit tree a chute spiraled there-around whose lower end terminates in a hopper, an elevator associated with the chute and arranged 35 to engage with and elevate objects from the hopper and deliver them to the upper end of the chute, and means for driving the elevator.

2. An apparatus of the character described, including the simulation of a fruit tree, a declining spiraled chute surrounding said tree, a receiving hopper into which the lower end of the chute discharges, an elevator associated with the said chute and hopper and formed with a carrier adapted to engage with an object simulating fruit in the hopper, and elevate the same and discharge it into said chute above the hopper, and means for driving the elevator. 45

3. An apparatus of the character described including an imitation fruit tree a declining chute formed with a spiraled section encircling said tree, a receiver adjacent the lower end of the chute, an elevator associated with said chute and receiver, and means for driving the elevator. 55

4. An apparatus of the character described, including the simulation of a fruit tree a declining circular chute encircling said tree, a receiver adjacent the lower end of said chute, an elevator associated with the chute, and arranged to pass through said receiver and elevate objects from said receiver and deliver the same into the chute above the receiver. 60 65

5. An apparatus of the character described, including the simulation of a fruit tree a declining chute, a section of which is spiraled around said tree, a receiver adjacent the lower end of the chute into which the chute delivers, means for elevating an object designed to simulate fruit from the receiver and delivering the same into the chute above the receiver. 70

6. An apparatus of the character described, including the simulation of a fruit tree, a declining chute spiraled there-around and an elevator associated with the chute adapted to elevate objects simulating fruit from the lower end thereof and deliver the same into the upper end thereof. 75 80

7. An apparatus of the character described, including the simulation of a fruit tree, a declining chute, a section of which is formed into a spiraled around said tree, an elevator associated with the chute and disposed to receive an object adapted to simulate fruit delivered from the lower or discharge end of the chute, and convey the same to, and discharge it into, the upper end 90 of the chute in a manner adapted to simulate fruit falling from said tree into said chute. 95

8. An apparatus of the character described, including an artificial tree a declining chute encircling said tree, an elevator associated with the chute and adapted to elevate objects from the lower end thereof and deliver the same into the upper end thereof, a circuitous fluid conduit adjacent 100 said tree having a transparent exposed section, a pump for circulating fluid through said conduit, and a common means for driving said elevator and pump. 105

9. In combination, an artificial fruit tree 105 a circuitous fluid conduit having an exposed transparent section connected with said tree, means for circulating a fluid through said conduit, a declining chute, a section of which is spiraled around said transparent section and tree, an elevator associated with the chute and provided with carriers through which fruit may be elevated from the lower end of the chute and delivered to the upper end thereof to simulate fruit falling from 110 said tree into said chute. 115

10. In combination, a pot, a circuitous fluid conduit having an exposed transparent section, means for circulating a fluid through said conduit, a declining circular chute, a section of which is spiraled around said transparent section, the lower end of said spiraled section disappearing in said pot, an elevator associated with the chute and provided with carriers through which fruit may be elevated from the lower end of the chute and delivered to the upper end thereof. 120 125

11. In combination, a container, a circuitous fluid conduit having an exposed transparent section, means for circulating a 130

fluid through said conduit, a declining chute adjacent said conduit, the lower end of said chute disappearing in said container, an elevator associated with said chute and provided with carriers, through which fruit may be elevated from the lower end of said chute, and delivered to the upper end thereof.

In testimony whereof we have signed our names to this specification in the presence of a subscribing witness.

WILLIAM F. REYNOLDS.
WILLIAM A. CATHEY.
